United States Patent

Des. 240,460

Patented July 6, 1976

240,460

REAR PROJECTION TRANSPARENCY VIEWER

Robert M. Simonelli, Palatine, Ill., assignee to
GAF Corporation, New York, N.Y.

Filed Dec. 18, 1974, Ser. No. 534,145

Term of patent 14 years

Int. Cl. D16—02

U.S. CL D16—17

FIG. 1

FIG. 2

FIG. 3

FIG. 4

FIG. 5

FIG. 6

FIG. 7

FIG. 1 is a front perspective view of a rear projection transparency viewer showing my new design;

FIG. 2 is a rear elevational view thereof;

FIG. 3 is a front elevational view thereof;

FIG. 4 is a right side elevational view thereof;

FIG. 5 is a left side elevational view thereof;

FIG. 6 is a top plan view thereof; and

FIG. 7 is a bottom plan view thereof.

I claim:

The ornamental design for a rear projection transparency viewer, substantially as shown.
